UNITED STATES PATENT OFFICE.

ISMAEL F. GALINDEZ, OF BUENOS AIRES, ARGENTINA.

ELECTRICAL GUN FIRING MECHANISM.

1,078,782.

Specification of Letters Patent. Patented Nov. 18, 1913.

Application filed December 7, 1912. Serial No. 735,394.

To all whom it may concern:

Be it known that I, ISMAEL F. GALINDEZ, a citizen of Argentina, captain in the Argentina Navy, and resident of Buenos Aires, 5 in the Province of Buenos Aires, Argentina, have invented a certain new and useful Improvement in Electrical Gun Firing Mechanism, of which the following is a true and exact description, reference being had to the 10 accompanying drawings, which form a part thereof.

The primary object of my invention is to provide simple, effective and reliable mechanism for the electrical firing of guns.

More specifically, the object of my invention is to provide means for supplying the current for igniting the explosive charge in the gun when the latter is discharged, which, 15 on the one hand, will be more permanent and reliable than an electrical battery, and on the other hand, will avoid the wiring and the danger of its disarrangement characterizing the present means of supplying current from a dynamo or transformer located 20 at some distance from the gun. Such wiring particularly in the case of war ships is complicated and readily susceptible of disarrangement when, as is usually the case, a 25 number of guns are supplied with current 30 from a common source.

In carrying out my invention, I employ a dynamo-electric machine, which may be any one of many known types of magnetos, as 35 the source of current for each gun, and employ in conjunction with the magneto a spring motor for operating it, and so mount the magneto and its operating mechanism that the latter will be automatically put under tension and locked in that condition 40 by the recoil of the gun after each discharge.

My invention also comprises novel means for releasing the spring actuating mechanism when the gun is to be discharged.

The various features of novelty which 45 characterize my invention, are pointed out with particularity in the claims annexed to and forming a part of this specification. For a better understanding of the invention, however, and of the advantages possessed by it, reference should be had to the accompanying drawings and descriptive matter in which I have illustrated and described one 50 of the forms in which my invention may be embodied.

55 Of the drawings: Figure 1 is a side elevation of a gun equipped with my improved

firing mechanism. Fig. 2 is a rear elevation of the gun shown in Fig. 1. Fig. 3 is a side elevation of a portion of the gun with parts removed and in section. Fig. 4 is a 60 section on the line 4-4 of Fig. 3. Fig. 5 is a section on the line 5-5 of Fig. 3; and Fig. 6 is a partial elevation taken similarly to Fig. 3, but with the parts in place which are removed in Fig. 3. 65

In the gun of known type somewhat conventionally illustrated in Figs. 1 and 2, the gun barrel A proper, is mounted in a sleeve or cradle B which is formed with trunnions B' journaled in a yoke C. The latter is pivoted on the pedestal D to turn about the vertical axle D'. To the cradle B is secured the usual recoil cylinders Y. 70

Y' represents the rods connecting the gun barrel to the pistons working in the cylinders Y. 75

The elevation of the gun may be manually varied by gearing not necessary to describe in detail which is mounted on the yoke C, is operated by the crank disks E and includes 80 a spur gear in mesh with a gear segment B² secured to the gun cradle. The gun may be manually turned about the axis of the swivel connection between the yoke C and pedestal D by means of crank disks EA and suitable 85 intermediate gearing, not necessary to describe in detail, which is mounted in the yoke C and includes a worm E' in mesh with the worm gear D² formed on the pedestal D.

The magneto which I employ to provide 90 the current for the electrical ignition of the explosive charge in the gun, comprises a main casing F which is secured to the front end of the sleeve or cradle B. As shown, the casing F is formed with one open side normally closed by the removable cover FA. The latter in turn is formed with a mechanism chamber F' open at one side, the opening being closed by a removable cover part F². The magneto proper is mounted within 100 the body of the casing F, the permanent field magnets G being secured to the inner side of the cover member FA by the bolts G'. The shaft H of the armature H' of the magneto is journaled at one end of the armature in 105 bearings formed in the casing parts FA and F². The spring actuating mechanism for the magneto and the releasable locking mechanism for said actuating mechanism are located in the mechanism chamber F'. 110

The actuating mechanism comprises a lever I secured to the shaft H and provided

with diametrically opposed arms I' , in which are mounted pins I^2 located at opposite sides of the shaft H . These pins are connected by helical springs J to pins K and K' secured to the casing part FA . The springs J which are relatively stiff, tend to hold the shaft H and lever I in the position, shown in full lines in Fig. 3, in which the axes of the pins I^2 , K and K' all lie in a plane passing through the axis of the shaft H . To utilize the recoil of the gun in automatically rotating the armature shaft H and lever I into the position shown in dotted lines in Fig. 3, after each discharge, an arm L is adjustably secured to the armature shaft H' . The arm L projects through an opening formed in the bottom wall of the mechanism chamber F' and normally lies in a slot A^2 formed in a member A' secured to the upper side of the gun barrel A . At its front end the bottom wall of the slot A^2 terminates in an inclined wall A^3 , and at the front end of the latter the shoulder A^4 is formed.

On the recoil movement of the gun the shoulder A^4 is carried from the position shown in full lines in Fig. 3 into the dotted line position in which the shoulder is at the right side of the arm L . As the gun returns home the shoulder A^4 engages the arm L and turns it in the clockwise direction to move the parts of the actuating mechanism into the dotted line position shown in Fig. 3. It is to be noted that unless the return movement of the gun is sufficient to bring the main portion of the slot A^2 beneath the lever L , the latter is not free to move from the dotted line position into the full line position shown in Fig. 3. As shown, the arm L is provided with a bifurcated hub portion encircling the shaft at the opposite sides of the hub of the lever I . Adjusting screws M passing through a portion L^2 of the lever L , and bearing against the arms I' of the lever I , are employed to lock the arm L to the lever I in the desired relative adjustment.

The means employed to releasably latch the actuating mechanism in the dotted line position shown in Fig. 3, whenever moved into that position, comprises a locking lever or trigger N which is journaled on the pin K . A spring O connected at one end to the casing part FA , and at the other end to the extension N^3 of the trigger N normally holds the latter in its locking position in which the arm N^3 engages a stop pin F^3 connected to the casing part FA . In its normal position the catch lug N' of the catch N is in position to engage the free end of the lever I and hold the latter in its dotted line position whenever moved into that position. To release the lever I from the trigger N when the gun is to be fired, a releasing lever P is fulcrumed at its lower end on the pin K . The releasing lever L is formed with a

chamber P' receiving a sliding bolt Q and a spring Q^2 , normally tending to hold the latter in the position in which its lower end is adapted to engage the lug N^2 on the trigger N when the releasing lever L is moved in the clockwise direction. A spring S connects the upper end of the lever P to a pin F^6 carried by the casing, and normally holds the lever P in the position shown in Fig. 3, in which it engages a stop pin F^4 carried by the casing. To permit the trigger N to snap back into its latching position after the lever I is released, even though the lever P may still be held in the discharge position, the bolt Q is provided with a pin or projection Q' which engages and is lifted by a cam R secured to the casing part FA as the lever P is turned on its fulcrum. The parts are so arranged that the bolt Q will release the trigger N only after a movement of the latter sufficient to release the lever I . But for the desirability of rendering it impossible for the firer to unconsciously prevent the relatching of the lever I in its dotted position on the recoil movement of the gun, the levers N and P might be rigidly or integrally connected.

To turn the lever P in the clockwise direction and thereby release the lever I when the gun is to be fired, a suitable pull T is connected to the upper end of the lever P . This pull may run to any convenient point for the operation by the hand or foot of the gun firer, or otherwise. As shown, the pull is arranged for quick and easy operation by the hand of the gun attendant controlling the elevation of the gun. For this purpose the handle E^2 journaled on the crank pin secured to one of the crank disks E , carries a sleeve-like support E^3 for the enlarged end portion T' of the pull member T . To the end portion T' is pivoted a ring T^2 in position to receive and to be actuated by one finger of the hand of the operator grasping the handle E^2 . The latter may thus exert the necessary pull on the member T at the very instant at which the proper elevation of the gun is secured. To permit of the necessary change in position of the pull member T , as the crank disk E to which it is secured is rotated, the member T is made flexible. For instance, it may advantageously be made of flexible wire. The member T fits snugly within but is longitudinally movable in a flexible casing U which is secured at one end to the casing member FA and at the other end to the sleeve member E^3 . This flexible sleeve should be sufficiently stiff and inextensible so that whenever a pull is imparted to the member T the latter will slide in the casing U . To effectually protect the casing U and to guard against its kinking I inclose the latter in a casing formed in part by the flexible armor V and in part by the pipe 130

section VA secured to the casing part FA. One end of the flexible armor V is secured to the sleeve part E² and the other to the outer end of the pipe section VA.

To permit the actuating mechanism to be manually moved into and locked in its operative condition when occasion demands, as when firing is to begin, a handle W is journaled on a boss F² carried by the casing part F² and surrounding the outer end of the shaft H. This handle is normally held against the stop pin F¹⁰ in a position in which it does not interfere with the movements of the armature shaft H by a helical spring W' connected at one end to the casing cover F² and at the other end to the handle W. The handle W carries a pin or projection W² adapted when the handle is turned to engage a shoulder X' at one end 15 of a cutaway portion of a disk X secured to the outer end of the shaft H, and thereby move the actuating mechanism from the full line position shown in Fig. 3 into the dotted line position shown in that figure. The cutaway portion of the disk X is so located 20 that when the handle W is in its retracted position in which it engages the stop pin F¹⁰ the armature shaft may have its necessary movements without interference by the handle W.

In operation after the actuating mechanism is locked in the dotted line position shown in Fig. 3, the release of the lever I, brought about by a pull exerted on the member T, permits the parts to turn into the full line position in Fig. 3. The tension of the springs J should be such that the movement thereby imparted to the armature shaft H when the lever I is released, will cause the 40 magneto to generate sufficient current to ignite the explosive charge in the gun. The actual ignition of the charge may be brought about in the usual manner by means not shown for electrically heating the bridge of 45 the primer up to the temperature of ignition. Those skilled in the art will understand of course that the armature of the magneto should preferably be disposed to generate its maximum electro-motive force 50 during the partial turn given the armature by the springs J. During the backward recoil movement of the gun following its discharge, the cam wall A³ engages the arm L and moves the latter in the counter-clockwise direction sufficiently to permit the shoulder A⁴ to pass to the right of lever as seen in Fig. 3. On the return movement of 55 the gun the shoulder A⁴ turns the arm L in the clockwise direction far enough to carry the free end of the lever I beneath the trigger catch N. If the gun jams and does not have a sufficient return movement the shoulder A⁴ or the outer end wall of the slot A² will prevent the subsequent release of the actuating mechanism; and if the back-

ward recoil movement of the gun is less than normal the actuating mechanism will not be automatically locked under tension, thus directing attention to the faulty operation of the gun.

It will be apparent to those skilled in the art that the mechanism described is both simple and effective, and is far more permanent and reliable than an electric battery which may or may not be employed as an auxiliary source of firing current. Furthermore, by making the source of the firing current individual to each gun, it is possible to avoid the wiring for connecting the gun to a dynamo or transformer located at some distance from the gun source of current. Such an arrangement, which is now generally employed, has been found unsatisfactory, particularly in the case of war ships, by reason of the complicated character of the wiring for suitably connecting all of the various guns to the source of current, and the danger of having this wiring injured in action, particularly in the case of cruisers, torpedo boat destroyers and other unarmored or lightly armored ships. The invention while of special value for use on war ships, may obviously be used with advantage on coast defense guns, and even on field artillery. Inasmuch as the spring actuating mechanism is directly connected to the armature of the magneto and the firing current is generated by an angular movement of the armature, which is but a fractional part of one turn, the generation of the firing current follows almost instantaneously after the release of the spring actuating mechanism for the magneto.

While in accordance with the provisions of the statutes, I have illustrated and described the best forms of my invention now known to me, it will be apparent to those skilled in the art that changes may be made in the form of the apparatus disclosed without departing from the spirit of my invention, and that under some conditions certain features of my invention may be used without a corresponding use of other features. In particular it is to be understood that the position of the dynamo electric machine and the manner in which it is actuated may vary and depend to some extent on the type of gun and the character of its mounting, the essential feature being that the actuating mechanism for the dynamo electric machine shall be so disposed and arranged that it will be put under tension by the relative movements of the gun and its mounting following the discharge of the gun.

Having now described my invention, what I claim as new and desire to secure by Letters Patent, is:

1. In combination with a gun and its recoil mounting, of electrical firing mechanism for the gun comprising a dynamo-elec-

tric machine, a rotatable armature, spring actuating mechanism connected to said armature and tending to hold the latter in one position, and means actuated by the movement of the gun in its mounting following its discharge for giving a partial turn to said armature to move the latter from said one position into a second position, and means for releasably locking said armature 10 in said second position.

2. In combination with a gun and its recoil mounting of electrical firing mechanism for the gun comprising a dynamo-electric machine of the magneto type, a rotatable armature, spring actuating mechanism connected to said armature and tending to hold

the latter in one position, and means actuated by the movement of the gun in its mounting following its discharge for giving a partial turn to said armature to move the latter from said one position into a second position, and means for releasably locking said armature in said second position, said dynamo-electric machine being adapted to generate its maximum electromotive force 25 during the movement of said armature from said second position into said one position.

ISMAEL F. GALINDEZ.
